UNITED STATES PATENT OFFICE

MORRIS KIRSCHSTEIN, OF BROOKLYN, NEW YORK

ILLUMINATING DEVICE

Application filed August 10, 1928. Serial No. 298,766.

This invention relates to illuminating devices and more particularly to improved electric illuminating sets of the type known as Christmas tree, or decorative lighting outfits.

- 5 It has become highly desirable to provide for the ready connection of one or more standard Christmas tree lighting outfits in parallel to a single electrical source to afford more or less illumination, or to ornamenteally illuminate large objects such as Christmas trees and the like. It is the object of this invention to provide an improved unitary device of the character described of simple construction and cheap manufacture, which is provided 10 with means for readily connecting an indefinite series of said devices in parallel across a single electric power supply to make a flexible unit for illuminating objects requiring greater or lesser amount of illumination.
- 20 In accordance with the present invention, a Christmas tree outfit having a plug for connecting with the electrical source is so constructed that it may receive another unit which need not have any plug for direct attachment to the electrical supply, but can be readily connected in parallel to said first unit and which has in addition means for receiving similar plugless units so that any number of units may be connected in parallel and all 25 supplied through the single plug on the first outfit.

A further object of the invention is to provide a device of the character described, which shall be simple in construction, comparatively cheap to manufacture, and practical and efficient to a high degree.

Other objects of this invention will in part be obvious and in part hereinafter pointed out.

40 The invention accordingly consists in the features of construction, combinations of elements, and arrangement of parts which will be exemplified in the construction hereinafter described, and of which the scope of application 45 will be indicated in the following claims.

In the accompanying drawing, in which is shown one of the various possible illustrative embodiments of this invention,

Fig. 1 is a plan view of a Christmas tree outfit embodying the invention;

Fig. 2 is a view showing two such Christmas tree outfits connected in parallel;

Fig. 3 is a view similar to Fig. 1 showing a slightly modified structure; and

Fig. 4 is a diagrammatic view of a modified construction.

Referring to the drawing, there is shown in Fig. 2 an electric decorative outfit A connected in parallel to an outfit B.

The outfit A comprises a number of the usual electric lamp sockets 10 adapted to receive lamps 10^a here shown as connected in series through conductors 11 in the manner well known in the art. Such outfits usually consist of a set of eight sockets, the end sockets 65 being provided with lead wires connected to the terminals of an attachment plug which may be connected to the usual 110-120 volt lighting circuit.

The outfit A is shown to comprise eight 70 sockets 10, connected to a usual attachment plug 12 by lead wires 13, 14. Where it is desired to illuminate larger objects or to obtain more illumination, the outfit B may be connected across the lead wires 13, 14, in 75 parallel. To this end, each of said lead wires 13, 14, has interposed therein an outlet socket 15 adapted to receive a plug member 16 forming the terminals of outfit B. Said outfit B also comprises eight electric lamp sockets 10^a 80 connected to each other by conductors 11^a. The outer two of said eight sockets 10^a of said outfit B are connected by wires 17, 17^a, to outlet sockets 15^a, similar to sockets 15. Conductors 18, 19 connect each of said plugs 85 16 to said sockets 15^a.

The socket 15 may comprise a substantially cylindrical body portion 20 of insulating material, preferably finished and shaped to resemble the sockets 10. Said body 20 is provided with a central longitudinal opening 21 extending therethru. Said opening 21 is widened at the mouth or plug receiving end of the body 20 to form a shoulder 22. A cylindrical hollow metallic member 23 is fitted into said opening 21 and comprises a flange portion 24 seated on said shoulder 22, and a bottom end wall 25 having an opening 26 therein. Said body 20 may be recessed adjacent the opening 21 to form a channel 27 between 90 95 100

the metallic member 23 and the body 20. Said member 23 in each of sockets 15 forms the current carrying part interposed in the leads 13, 14. To make the connection, the lead 5 13 may be split to provide two wire ends, one of which may be inserted in opening 26 and soldered to the end wall 25, the other of which may be extended into channel 27 and soldered to said member 23 as at 28. It will be understood 10 that socket 15 is similarly interposed in lead 14, and that sockets 15^a at each end of outlet B are likewise connected to conductors 17, 18 and 17^a, 19 respectively. Each of plug members 16 comprises a cylindrical insulating body 29 of U-shaped cross-section having an opening 30 in the bottom wall 29^a thereof. A short cylindrical metallic post 31 may be inserted thru said opening 30. Said post 31 is formed within a flange 32 at the upper end 20 thereof seated on said bottom wall 29^a and fixed to the body 29. The lower portion of said post 29 is preferably split longitudinally as at 33 to provide a resilient end portion 34. The conductor wire 18 may be connected to said post 31 as by soldering the end 35 of said wire to flange 32 of said post 31.

It will now be obvious that to connect outfit B in parallel and outfit A, it is merely necessary to insert the resilient end portions 34 of 30 plug members 16 into the openings 35 of hollow members 23 of sockets 15.

Any number of outfits B may be added, the plugs 16 of each added outfit being attached to sockets 15^a of the preceding outfit.

35 A consumer need buy only one set A and then purchase standard unit B from time to time as required to add to the series which may be connected thru plug 12 to a single outlet socket. The sets B may very easily and 40 simply be attached or detached since each of said sets includes a pair of plugs 16 for connecting to a preceding outfit and a pair of sockets 15^a for receiving the plugs of a succeeding outfit.

45 Fig. 3 shows a modified construction of the complementary sockets and plugs for connecting the sets to one another. In this construction the sockets 36 interposed in lead 13^a comprises an ordinary electric lamp socket similar to socket 10, and adapted to receive a lamp when not used for connecting to another set. The plug 37 connected to the conductor 18^a comprises a metallic screw threaded shell member 38 receivable in socket 36. Said plug 37 is made somewhat similar to an ordinary screw plug. However, the threaded member 38 is provided with a metallic bottom wall 39. When attached to the socket 36, said bottom wall 39 forms an electrical connection 50 between the central contact and the shell of said socket, thus completing the circuit thru said socket and lamps in the remaining sockets in the set.

It will be apparent that the last outfit in 60 the series may receive ten lamps instead of

eight when the modified plugs and socket 37, 36 are used.

Fig. 4 diagrammatically shows a modified construction illustrating an adaptation of the invention to decorative sets comprising a 70 number of sockets connected in parallel. Outfit A' shown in Fig. 4 comprises eight usual sockets 110^b connected in parallel across leads 13^b, 14^b attached to an attachment plug 12^b. Sockets 15^b similar to socket 15 may be interposed in said leads 13, 14. Outfit B' comprises sockets 10^c connected in parallel across leads 18^c, 19^c. Similar sockets 15^c may be interposed in said leads 18^c, 19^c, which terminate in single terminal plugs 16^c similar to 75 plugs 16. Said plugs 16^c may be received in sockets 15^b of outfit A' for detachably connecting outfit B' to said outfit A'. Additional outfits similar to outfit B' may be added by plugging to sockets 15^c as will now be 80 understood.

It will thus be seen that there is provided a device in which the several objects of this invention are achieved, and which is well adapted to meet the conditions of practical 85 use.

As various possible embodiments might be made of the above invention, and as various changes might be made in the embodiment above set forth, it is to be understood that all 90 matter herein set forth or shown in the accompanying drawings is to be interpreted as illustrative and not in a limiting sense.

Having thus described my invention, I 95 claim as new and desire to secure by Letters Patent:—

1. A unitary Christmas tree lighting set comprising a set of electrically connected lamp sockets, an attachment plug connected with the socket at each end of said set, and complementary sockets interposed in the circuit between each of said plugs and the adjacent socket adapted to receive similar attachment plugs from a second lighting set. 105

2. A unitary Christmas tree lighting set comprising an attachment plug adapted to be inserted to a power outlet, a plurality of lamps connected together in series, lead wires connecting said lamps with the circuit terminals of said attachment plug, and sockets formed to receive single terminal plugs interposed in said lead wires. 110

3. In an electric illuminating device of the character described, in combination, a Christmas tree set comprising an attachment plug adapted to be attached to an electric power outlet, a plurality of electric lamps connected in series, lead wires connecting said lamps with the terminals of said attachment plug, sockets adapted to receive complementary plugs interposed in said lead wires and a second Christmas tree set comprising a plurality of lamps connected in series and complementary plugs at each end of said set attached to said sockets. 120 125 130

4. In an electric illuminating device of the character described, in combination, a Christmas tree set comprising an attachment plug adapted to be attached to an electric power outlet, a plurality of electric lamps connected in series, lead wires connecting said lamp with the terminals of said attachment plug, sockets adapted to receive complementary plugs interposed in said lead wires, a second 5 Christmas tree set comprising a plurality of lamps connected in series and complementary plugs at each end of said set attached to said sockets, and similar sockets adapted to receive complementary plugs from another 10 15 Christmas tree set interposed in said second set between said plugs and the end lamps of said second set.

In testimony whereof I affix my signature.
MORRIS KIRSCHSTEIN.
